RAISABLE STEPLADDERS

Roy D. Deahl, New York, N. Y.

Application June 22, 1955, Serial No. 517,123

2 Claims. (Cl. 228—12)

This invention relates to new and useful improvements in stepladders and elevating devices.

More particularly, the present invention proposes the construction of an improved elevator stepladder which can be used as a low stepladder or as a high stepladder easily and conveniently and at will.

As a further object, the present invention proposes forming the elevator stepladder with an upper tread which can be used either as a step or tread or as a tray for holding buckets, cleaning equipment and other such articles.

Another object of the invention proposes constructing the elevator stepladder with a ready accessible crank so that the user may raise or lower the ladder to suit the particular need at the time.

Still further, the present invention proposes forming the ladder with a quick release device so that it can be quickly and safely lowered for stepping off the ladder.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an elevator stepladder constructed and arranged in accordance with the present invention.

Fig. 2 is a rear view of the ladder shown in Fig. 1.

Fig. 3 is a side view of the ladder shown in Figs. 1 and 2 but in raised position.

Fig. 4 is a sectional view with parts broken away and taken on line 4—4 of Fig. 3.

Fig. 5 is a front view of an elevator stepladder showing a modification of the present invention.

The elevator stepladder, in accordance with the first form of the invention illustrated in Figs. 1 to 4, inclusive, is designed generally by the reference numeral 15.

Elevator stepladder 15 has a step member 16 with a horizontal lower tread portion 17, a vertical riser portion 18 and a horizontal upper portion 19. Preferably the height or length of the riser portion 18 is relatively great and the horizontal upper portion 19 contains an upturned ledge or flange 20 to make it adapted for use as a table to hold articles thereon such as cleaning equipment, paint buckets and the like.

A base 21 is provided with rollers or wheels 22 and supports the step member in the following manner. An upright support post 23 is mounted on the base 21, the base 21 being provided with a threaded opening 24 into and through which the threaded lower end 25 of the post 23 extends. A lock nut member 26 may be provided on the threaded end 25 of the post 23 adjacent the base 21.

Slidably mounted on the post 23 is a slide member 27 in the form of a sleeve extending over and around the post. A bracket clamp member 28 clamped to the slide member 27 and secured to the riser portion 18 of the

2

step member 16 as by screws 29 secures the step member to the slide member 27.

Upright support post 23 has an axial inner threaded chamber 30 into which movably fits a screw column 31 having an upper end 32 extending from the post and on which is mounted a screw column gear 33 which is fixed to the screw column for movement therewith.

Fixed to the horizontal upper portion 19 of the step member 16 is a plate 34 from which extends a dependent alignment pin 35. Screw column gear 33 is disposed beneath the horizontal upper portion 19 of the step member 16 and has an axial recess 36 to receive the alignment pin 35 for rotation of the screw column gear about the alignment pin.

A slide member gear 37 is rotatably mounted on a horizontal stub axle extension 38 from the slide member 27 for mating meshing action with the screw column gear and a crank 39 is connected with the axle extension 38 and slide member gear 37 to rotate the gear 37.

Means to prevent the slide member 27 from rotating on the upright support post 23 as the crank 39 is turned is provided as follows. A pin or screw 40 extends through the wall of the slide member 27 into the axial bore or chamber of the upright post 23 through a vertical slot opening or keyway 41 in the post.

The operation of the elevator stepladder is simple and convenient. The operator or user steps on the lower tread or step and works from that tread or step when a low stepladder is needed. The upper tray or horizontal portion provides a table to hold work materials or can be used as an upper step or tread. When a higher ladder is desired, the crank 39 may be turned which moves the slide member gear which in turn moves the screw column gear which then turns the screw column and raises the step member. The step member may be lowered by turning the gear crank in the opposite direction.

The modification of the present invention illustrated in Fig. 5 is characterized by the provision of an elevator stepladder 50 having a base 51 mounted on rollers or wheels 52 with an upright post 53 extending from and fixed to the base. A slide member 54 in the form of a sleeve slidably fits on the post 53 and a step member 55, having a lower horizontal tread portion 56, a riser portion 57 and an upper horizontal portion 58, is secured to the slide member 54 as by bracket 59.

Also mounted on the base 51 is a vertical rack 60 and a pinion 61 for the rack is rotatably mounted on the rise portion 57 of the step member 55 as by pillow blocks 62 and 63. A crank 64 is connected to the peripheral portion of the pinion 61 to rotate the pinion on the rack and move it up and down the rack by such rotation. A ratchet pawl 65 is movably mounted on the step member 55 above the pinion 61 and operatively and releasably connected with the pinion 61 to limit movement of the pinion in one direction until released. The ratchet pawl 65 is mounted on a pin or shaft 66 secured by a bracket 67 to the riser portion 57 of the step member 55. A spring 68 on the pin 66 biases the ratchet pawl 65 into pinion engaging position.

Post 53 is hollow, having an axial bore or chamber 69 and a pin 70 extends from the slide member 54 into and through a vertical slot or keyway 72 in the post 53.

A bumper spring 73 is mounted in the hollow post with one end 74 bearing against the base 51 and the other end bearing against the pin 70. The spring 73 is of a strength slowly to let the step member descend under the weight of the user of the ladder after the ratchet pawl is released. This provides a quick and safe means to lower the ladder for stepping off the ladder.

While I have illustrated and described the preferred embodiments of my invention, it is to be understood that

I do not limit myself to the precise constructions herein disclosed and that various changes and modifications may be made within the scope of the invention as defined in the appended claims.

Having thus described my invention, what I claim as new, and desire to secure by United States Letters Patent is:

1. An elevator stepladder comprising a base, an upright support post mounted on the base, a tubular slide member slidably mounted on the post, a step member connected to the slide member and having a horizontal lower tread portion and a flat vertical riser portion and a horizontal upper portion, means to raise and lower said slide and step members on the post, said means to raise and lower said slide and step members on the post being a vertical rack mounted on the base and a pinion rotatably mounted on the step member and slide member, a crank handle connected with the pinion to rotate the pinion on the rack, a ratchet pawl movably mounted on the step member and operatively and releasably connected with the pinion to limit movement of said pinion in one direction until released, spring means biasing said pawl to operative position, and means to prevent the slide member from rotating on the post, said means being a pin extending from the slide member, said post being hollow and having a vertical keyway slot slidably to receive one end of said pin.

2. An elevator stepladder comprising a base, an upright support post mounted on the base, a tubular slide member slidably mounted on the post, a step member connected to the slide member and having a horizontal lower tread portion and a flat vertical riser portion and

5

a horizontal upper portion, means to raise and lower said slide and step members on the post, said means to raise and lower said slide and said step members on the post being a vertical rack mounted on the base and a pinion rotatably mounted on the step member and slide member, a crank handle connected with the pinion to rotate the pinion on the rack, a ratchet pawl movably mounted on the step member and operatively and releasably connected with the pinion to limit movement of said pinion in one direction until released, spring means biasing said pawl to operative position, and means to prevent the slide member from rotating on the post, said means being a pin extending from the slide member, said post being hollow and having a vertical keyway slot slidably to receive one end of said pin, and a bumper spring mounted in the hollow post and having one end bearing against the base and another end bearing against said pin.
